Inventor:
Edmund B. Wedmore,
by *Albert G. Davis*
His Attorney.

UNITED STATES PATENT OFFICE.

EDMUND BASIL WEDMORE, OF GOLDER'S GREEN, ENGLAND, ASSIGNOR TO GENERAL ELECTRIC COMPANY, A CORPORATION OF NEW YORK.

PROTECTIVE DEVICE.

Application filed December 10, 1919. Serial No. 343,805.

To all whom it may concern:

Be it known that I, EDMUND B. WEDMORE, a subject of the King of Great Britain, residing at 1 Sneath Avenue, Golder's Green 5 N. W. 4, England, have invented certain new and useful Improvements in Protective Devices, of which the following is a specification.

My invention relates to protective systems and particularly to systems of the pilot wire type, and has for its object to extend the range of such systems so as to enable the protective apparatus to take care of faults between phases as well as faults to earth in 15 a more effective manner than has hitherto been possible.

It is desirable to design such protective apparatus to give a low setting on faults to earth, but the relays with such a setting must 20 not be affected by conditions which arise when the system is subjected to a severe short circuit between phases. The heavy currents flowing under such a condition cause a rise of potential on the pilot wires, 25 resulting in a flow of capacity current. Current may also flow through the pilot wires due to lack of balance between the voltages set up in the protective transformers. These conditions may result in the protective apparatus operating and the switches being 30 opened on sound feeders as well as on a faulty one.

The relays must not be set to operate except at current values above the limits 35 reached by these capacity currents and unbalanced currents respectively. In certain designs for example, it has been found that if the apparatus is adjusted to withstand say 6000 amperes on a work-shop test, it is necessary, in practice, to employ relay settings 40 as high as 200 to 400 amperes. The object of my invention is to extend this range, thus enabling lower settings to be employed or higher short circuit currents to be withstood, as may be required.

It is particularly important to obtain low settings on faults to earth, but on faults between phases, relatively higher settings may be employed with satisfaction, and my invention consists in the employment of a combination of apparatus giving low settings 50 on faults to earth, and able to withstand very heavy short circuit currents.

The short circuit currents flowing on

faults to earth are sometimes limited by resistance in the earth connection, and do not reach the same maximum value as is reached on short circuits between phases. According to my invention, I employ a combination of apparatus which is relatively sensitive 55 for faults to earth, and able to withstand the relatively low maximum currents flowing on these faults, while it is relatively insensitive on faults between phases, and able to withstand very heavy currents flowing 60 under these conditions.

As hitherto constructed the protective transformers have commonly been designed with an air gap in the magnetic circuit, and such transformers are influenced by their 65 surroundings, which may affect the permeability of the air gap. Such transformers are also liable to be affected by stray magnetic fields from adjacent conductors. It is a further object of my invention to dispose 70 of this difficulty and this is done by so disposing the parts that the air gaps are shielded by surrounding them with magnetic material.

My invention will be better understood 75 from the following description taken in connection with the accompanying drawing and its scope will be pointed out in the appended claims.

In the accompanying drawing, Figure 1 is 80 a diagrammatic representation of a protective system embodying my invention, and Fig. 2 is a diagrammatic representation of a modification of my protective transformer.

Referring to Fig. 1, lines 1, 2 and 3 represent the conductors of a three-phase distribution system, parts of three sections of the line being shown. At the ends of the middle section of the line there are shown co-operating transformers A and B connected in opposition, each of which comprises a core 4 preferably in the form of a ring or cylinder surrounding the conductors 1, 2 and 3. This core is shown continuous but it may have air gaps symmetrically disposed with reference to the conductors. The core 4 is provided with either a continuous winding or a winding in the form of three separate coils 5 symmetrically disposed with relation to the conductors 1, 2 and 3. The outer core 4 corresponds to a well-known design of core balancing transformer, which is sensitive to faults to earth and may be readily

balanced to withstand the currents flowing in sound sections of the system, to faults to earth in another section.

Within the core 4 I provide a fixed star-shaped or three-legged member 6, the legs of which are located respectively between the three phase conductors 1, 2 and 3, air-gaps being left between the outer ends of the legs and the outer core 4. The legs of the core 6 are provided with windings which will function to disconnect the section on short circuits occurring between phases. These windings may be connected in series and connected to the pilot wire system.

In order that the windings shall be affected by faults between any two phases or all three phases I may employ either windings on two legs only or on three legs, one of the windings being reversed or on three legs one of them having a different number of turns.

In the present instance, I have shown windings in opposite senses on two legs of the inner core. The inner and outer cores with the three phases forming the primary windings and provided as described with secondary windings, constitute a polyphase protective transformer giving protection against faults between phases. By the use of relatively large air gaps or relatively few turns or by means of both devices, the apparatus is made relatively insensitive and able to withstand without undue loss of balance relatively higher fault currents flowing to another section than the outer core itself.

The windings on the inner core are of relatively low self-induction and may be conveniently connected in series with the winding or windings on the outer portion, in which case it is necessary only to employ one outgoing and one return conductor for coupling the transformer to the corresponding transformer on the other end or side of the cable or apparatus protected. Alternatively separate outgoing pilot wires may be employed as shown in Fig. 1. In this arrangement, wire 7 leads from the windings on the inner core 6 of transformer A at one end of a section of the line 1-2-3 through the operating relays 8 to the windings on the inner core 6 of the transformer B at the other end of the section and wire 9 leads from the windings 5 on the outer core 4 of transformer A through the operating relays 10 to the windings 5 on the outer core 4 of transformer B. The relays 8 will operate on a fault between phases and relays 10 on a fault to earth in the apparatus or section protected by the cooperating transformers A and B. 11 is the common return pilot wire, the two transformers A and B being connected for opposing E. M. F.'s. With the former arrangement, a single relay at each end is all that is re-

quired. With the latter arrangement, the separate relays employed at the two ends may then be adjusted independently, so that the settings may be altered independently for faults to earth and faults between phases.

The operation of the system is as follows:

(1) *Earth fault in the section protected by the apparatus.*

Under normal conditions on the line 1-2-3, since the windings 5 of transformers A and B are connected for opposing electromotive forces, no current will flow through relays 10. An earth fault in the section protected by the apparatus will cause an unbalancing of the voltages in the windings 5 of transformers A and B and current will flow, say from windings 5 of transformer A through pilot wire 9, through relays 10 to windings 5 of transformer B and back through pilot wire 11 to windings 5 of transformer A. Relays 10 will, therefore, operate to open the circuit of conductors 1, 2 and 3 and isolate the faulty section.

(2) *Fault between phases in the section protected by the apparatus.*

Under normal conditions on the line 1-2-3, since the windings on the inner cores 6 of the transformers A and B are connected for opposing electromotive forces, no current will flow through relays 8. A fault between phases on the section protected by the apparatus will cause an unbalancing of the voltages in the windings on the inner cores 6 of the transformers A and B and current will flow, say from the windings on the inner core 6 of transformer A through pilot wire 7 through relays 8 to the windings on the inner core 6 of transformer B and back through pilot wire 11 to the windings on the inner core 6 of transformer A. Relays 8 will, therefore, operate to open the circuit of conductors 1, 2 and 3 and isolate the faulty section.

(3) *Fault to earth in a section of the system fed through the section protected by the apparatus.*

A fault to earth in a section of the system fed through the section protected by the apparatus will produce equal electromotive forces in the windings 5 of the transformers A and B, and since these windings are connected in opposition, no operating current will flow in relays 10. Consequently relays 10 remain inoperative and the circuit in the sound section is not interrupted.

(4) *Fault between phases in a section of the system fed through the section protected by the apparatus.*

A fault between phases in a section of the system fed through the section protected by

the apparatus will produce equal electromotive forces in the windings on the inner cores 6 of transformers A and B, and since these windings are connected in opposition,

5 no operating current will flow in relays 8. Consequently relays 8 will remain inoperative and the circuit in the sound section is not interrupted.

In the construction described, the outer 10 ring portion serves as a magnetic shield to the air gaps between the outer and inner cores. The arrangement described is one convenient for production, but I do not confine myself to this form. Fig. 2 illustrates a 15 modification of my protective transformer in which the second set of windings is carried on polar projections 12 on the outer core, projecting between the current carrying conductors 1, 2 and 3, and having an air gap 20 at the centre.

The apparatus above described may be conveniently mounted in a cable box of the type usually employed for supporting the terminals of a 3-phase transformer.

25 An alternating current system may be provided with as many pairs of such transformers as there are feeders and apparatus for which it may be desired to provide a protective device. The feeder, section, or 30 apparatus where the fault occurs, will be open circuited without disturbing other portions of the system which are sound. The word "section" in the claims is intended to cover a feeder, transformer or any other 35 portion of a system where protection is applicable.

What I claim as new and desire to secure by Letters Patent of the United States, is,—

1. In protective devices for alternating 40 electric current systems in which the input of electric energy into a section of the system is normally balanced against the output from said section, the combination of balancing devices which are relatively sensitive 45 on faults to earth only, and balancing devices which are insensitive on faults to earth and relatively insensitive on faults between phases.

2. An alternating electric current system 50 provided with a protective transformer at two points of the system, windings on said transformers interconnected to balance the input of electrical energy into the section between said points against the output from said section, certain windings on each of said transformers being interconnected to produce a resultant electromotive force upon faults to earth in the section and certain windings on each of said transformers being

interconnected to produce a resultant electromotive force upon faults between phases, said transformers being constructed so that the windings responsive to faults between phases are relatively insensitive while the windings responsive to faults to earth are 65 relatively sensitive.

3. In combination with a three-phase electric system, protective transformers at two points of said system, said transformers comprising inner and outer cores, air gaps 70 between said cores, conductors between said cores in series relation with said system, windings on said cores interconnected to balance the input of electrical energy into the section between said points against the 75 output therefrom, the windings on said outer cores being adapted to yield operating currents on faults to earth in said section and the windings on said inner cores to yield operating currents on faults between 80 phases in said section and said outer core forming a shield for said air gaps.

4. The combination of a three-phase current system, a protective transformer comprising a three-legged inner core provided 85 with windings, an outer core provided with windings, air gaps for said inner core, and conductors between said cores in series relation with the conductors of said system, said outer core acting as a shield for the air gaps 90 of said inner core.

5. In combination with an alternating electric current system, protective transformers at two points of the system, said 95 transformers comprising inner and outer cores, windings on said cores, conductors between said cores in series relation with said system, said windings on the outer cores of said transformers being interconnected for opposing electromotive forces and relatively 100 sensitive on faults to earth and said windings on the inner cores of said transformers being interconnected for opposing electromotive forces and relatively insensitive on 105 faults between phases.

6. A protective transformer for alternating electric systems, comprising an outer core provided with secondary windings connected in series, a three-legged inner core constructed to provide a high reluctance in the path of each leg, secondary windings on a plurality of the legs of said inner core connected in series, and a primary winding comprising conductors placed between each of the legs of said inner core.

In witness whereof, I have hereunto set my hand this 24th day of November, 1919.

EDMUND BASIL WEDMORE.
